UNITED STATES PATENT OFFICE.

JOSEPH D. DENBURGER, OF LENTS, OREGON.

MAIL CATCHING AND DELIVERING APPARATUS.

1,225,594.

Specification of Letters Patent.

Patented May 8, 1917.

Application filed May 22, 1916. Serial No. 99,178.

To all whom it may concern:

Be it known that I, JOSEPH D. DENBURGER, a citizen of the United States, residing at Lents, in the county of Multnomah and State of Oregon, have invented certain new and useful Improvements in Mail Catching and Delivering Apparatus, of which the following is a specification.

My invention relates to new and useful improvements in a mail catching and delivering apparatus.

The primary object of the invention is the provision of an apparatus of this character which will receive the mail on the train and deliver the mail from the train to a receptacle mounted adjacent the track.

A further object of the invention is the provision of a receptacle secured or mounted adjacent the track in such a manner that it can be adjusted to receive the mail from trains traveling in either direction.

A still further object of the invention is the provision of means for closing the receptacle after it has caught the mail and the provision of a catch for holding the receptacle in closed position.

Another object of the invention is the provision of a receptacle adapted to be secured to the car for receiving the mail from a crane mounted adjacent the track, said receptacle being so mounted that it can be swung into the car when not in use.

A further object of the invention is the provision of means for hanging a bag from the car whereby it may be deposited into the receptacle along the track, and means for supporting a bag along the track whereby it may be deposited in the receptacle connected to the car.

With these and other objects in view the invention consists in the novel details of construction and arrangement of parts which will be more clearly understood from the following description and drawings, in which,

Figure 1 is a side view of the track receptacle in closed position,

Fig. 2 is a front view of the track receptacles, showing them in open position, ready for receiving a mail bag,

Fig. 3 is a vertical section through the track receptacle showing it open for receiving the mail sacks,

Fig. 4 is a fragmental transverse vertical section through a car, showing the receptacle secured to the car, said receptacle being

shown within the car and shown in dotted lines swung out of the car ready for receiving the bag,

Fig. 5 is a fragmental detail showing a rear view of the guiding member for the receptacle,

Fig. 6 is a fragmental vertical section through the receptacle showing the locking catch,

Fig. 7 is a fragmental side view of the releasing means for the catch,

Fig. 8 is a fragmental side view of the stand for the track crane, parts being shown in section,

Fig. 9 is a transverse section on the line 9—9 of Fig. 8, looking in the direction of the arrows,

Fig. 10 is a section on the line 10—10 of Fig. 3,

Fig. 11 is a fragmental side view, partly in section, of the arm for supporting the bag to be delivered,

Fig. 12 is a fragmental elevation of a detail, and

Fig. 13 is a longitudinal section of the closure plate.

In the drawings, the numeral 1 indicates the stand of the track crane, and said stand is provided on the lower end with a flange 2 whereby it may be secured to a tie or other suitable support by means of bolts 3 or other suitable fastening elements. The stand 1 is provided with a vertical opening, the purpose of which will be presently described, and a flange 4 is formed on the top of the stand and has the circumferentially spaced notches or openings 5 therein. Circumferentially spaced staples 6 are secured to the stand beneath the flange 4 and the purpose of which will be presently described. The track crane comprises a post 7 the lower end of which is adapted to be received in the opening formed in the stand 1, as is more clearly illustrated in Fig. 8 of the drawings.

A collar or band 8 is adapted to be secured to the post 7 above the flange 4 of the stand 1 and an arm 9 is pivotally connected to the band 8 and is adapted to be received in one of the notches or openings 5 when in lowered position. The arm 9 is provided with an opening through which one of the staples 6 may pass and to lock or secure the arm in lowered position, it is only necessary to engage a padlock or other suitable fastening means through the staple. By removing the padlock or other fastening element the arm

110

may be swung upwardly until it disengages from the notch or opening 5 and the post 7 can then be rotated in the stand for the purpose as will be presently described.

5 Vertically spaced rods 10 and 11 are secured to each side of the post 7 and the mail bag receiving receptacles are adapted to be secured to these rods. The mail bag receiving receptacles are each composed of two 10 swinging sections, the upper section being swung from the rod 10 and the lower section being supported upon the rods 11. These receptacles are more particularly shown in Figs. 1, 2 and 3 of the drawings and the 15 upper sections are indicated at 12 and the lower sections at 13. The lower sections 13 are of such a width whereby they will be received between the sides of the upper receptacles 12. The sections 12 and 13 are supported upon the rods 10 and 11 by the rods 20 passing through eyelets or sleeves 14 which are formed upon plates 15 which are secured to the sections of the receptacles in any desired manner. These eyes or sleeves are of 25 such an interior bore as to allow the sections to swing freely upon the rods. The upper edges of one side of the lower receptacle 13 are cut on an angle, as indicated at 16, thereby leaving a space between the lower 30 edge of the section 12 and the upper edge of the section 13, as is more clearly illustrated in Fig. 1 of the drawings and the purpose of which will be presently described. The lower sections 13 are also cut away at the 35 rear from the top edge to form the space indicated at 17 whereby an opening is formed between the upper section and lower section. The purpose of this opening will be later described. An L-shaped guide strip 18 is secured 40 to the rear of each lower section 13 of the receptacle, the detail of construction being more clearly illustrated in Figs. 5 and 10 of the drawings, and an L-shaped plate 19 is secured to the lower edge of the top 45 section 12 and is provided with an extension 20 adapted to extend under the L-shaped guide strip 18 secured to the lower section.

The lower sections 13 are provided on the front edge with a flange indicated at 21, 50 said flange having an opening 22 formed near each end thereof. Spring catches 23 are secured to the upper sections and are provided with the enlarged heads 24 which are adapted to pass through the openings 22 and engage the underside of the flange 21. When the enlarged heads 24 engage the underside of the flange 21, the sections are 55 locked together. A rod 25 is mounted on the interior of the upper section 12 by means 60 of the ends passing through the sides of the sections and one end of said rod 25 is square, as indicated at 26, more particularly in Fig. 7 of the drawings. Arms 27 are secured to the rod 25 near each end thereof and said 65 arms 27 are adapted to pass through slots formed in the upper section 12 and on the outer ends carry a rod 28 which is secured to the spring catch arms 23. By engaging the squared end 26 with a key the rod 25 may be rotated thereby drawing the spring- 70 catch arm 23 inwardly toward the receptacle whereby the enlarged head 24 may be withdrawn through the slots 22 formed in the flange 21.

Rods or arms are secured to the post 7 75 beneath the receptacle and on each side of the post, and said rods or arms comprise the sections 29 and 30 hingedly connected together at 31. The section 29 is provided on the outer end with a recess indicated at 32 more particularly in Fig. 11 of the drawings, and a coil-spring 33 is secured in said recess and is also connected to the extension 34 formed on the inner end of the section 30. The hinge connection 31 is formed by the extension 34 extending into a slot formed in the end of the section 29 and a pin 35 which passes through the end of the section 29 and the extension 34. 80

For receiving the mail upon a car, and delivering a bag from the car to the track receptacle, I provide a receptacle and supporting arm of the same detail construction as described for the track crane. The construction of the car apparatus is more particularly shown in Fig. 4 of the drawings and the numeral 36 illustrates a section of a car of ordinary construction, and 37 illustrates the door opening. A post 38 is mounted on the interior of the car adjacent the door 90 95 opening 37 by means of the ends of the post passing through the top and bottom of the car. Upper and lower rods 40 and 41, respectively, are secured to the post and the rods 40 support the upper section 42 of a receptacle of the same construction as described for the track crane and the rods 41 support the lower sections 43 of the receptacle. The remaining parts of the receptacle 100 are of the same detailed construction as that previously described for the receptacle on the track crane. A rod or arm 44 is secured to the post 38 above the rods 40 and said rod 44 has an arm or section 45 hingedly connected thereto in the same manner as 105 that described for the rods or arms 30 in the track crane. For receiving the mail sacks from the track crane, the receptacle is swung outside of the car, as is illustrated in dotted lines, and when not in use is swung into the 110 car, as illustrated in full lines in Fig. 4 of the drawings.

In order to removably hold the post 38 in substantially rigid positions with respect to the car floor, so as to consequently hold 115 the receptacle carried thereby in various adjusted positions within and exteriorly of the car and to incidentally facilitate rotation of the post I have arranged a plate 46 about the post 38 and secured the same to the 120 125 130

floor. This plate is provided with a plurality of uniformly spaced openings 47. A clamp 48 is secured to the post above the plate while a stud 49 is formed thereon. An operating handle 50 is pivoted to the stud and has a pin 51 pivoted to the inner end thereof and slidably in an opening in the clamp and adapted to removably engage one of the openings 47 for locking purposes.

10 In Fig. 12, I have illustrated a modified form of receptacle on the car and in this instance have provided the rear end of the lower section with another opening 52 on the inclined edge of the section opposite the 15 opening 17. A closure plate 53 is adapted to be removably associated with the lower section to close the openings 17 and 52. The preferable means for connecting the plate comprises spaced legs 54 rigidly connected 20 to the lower sides of the plate and removably straddled about the section 43. As will be appreciated the arms will pass through the outer of these openings during the 25 progress of the train, the plate serving to close the inner opening. When the end of the line is reached the plate 53 may be shifted to close the other opening and the receptacle swung into proper position.

Having fully described the details of construction it is thought that the operation and advantages of my device will be clearly understood. When the mail sacks are to be transferred from one car to the crane and from the crane to the car, the receptacle and 35 arm of the post 38 of the car are swung until they extend outwardly from the door, as is clearly illustrated in dotted lines in Fig. 4 of the drawings, and the post 7 of the track crane is swung so as to bring the 40 open sides of the receptacle on the post facing the approaching train. The sections 12 and 13 and 42 and 43 of the crane receptacle and car receptacle, respectively, are swung upon the supporting rods to assume the position more clearly illustrated in Figs. 2 and 45 3 of the drawings, whereby the front of the receptacles will open to receive the bags. The bag to be delivered from the car to the crane is hung upon the section 45 secured to 50 the rod 44 and the bag to be delivered from the crane to the car is hung upon the section 30 secured to the rod 29. As the train approaches the bag carried thereby will be deposited into the receptacle upon the track 55 crane and that bag carried by the track crane will be deposited in the receptacle carried by the car. The force of the bag hitting the back wall of the lower section of the receptacle will swing such section downwardly thereby closing the upper section over the 60 lower section and the enlarged heads 24 of the spring-catches 23 will pass through the openings 22 formed in the flanges 21 and the sections will be locked together by said 65 enlarged heads engaging the underside of

the flange. It will be understood that the operation is the same in both the crane receptacle and the car receptacle, and by having the sections 30 and 45, respectively, hingedly connected to the rods 29 and 44, 70 it will be seen that the said sections will give when the bag contacts with the receptacle and that the spring 33 will return the sections to their normal position after depositing the bags. By having the upper edge of the 75 lower receptacle inclined, as indicated at 16, it will leave a space for the arms to pass therethrough and they will also pass through the opening 17 in the rear of the lower section of the receptacle. 80

The post 7 of the track crane is preferably mounted between the two tracks of the railroad when double tracks are used and after the bag is caught the post may be rotated so that the receptacles will extend 85 parallel with the track. If my apparatus is to be used with a single track railway, the post 4 will be mounted adjacent one side of the track. It will be seen that by rotating the post 7, the receptacles may be brought 90 into such a position as to receive the sacks from a train traveling in either direction. After the post 7 is rotated it is held in its adjusted position by means of the arms 9 engaging in one of the notches 5 formed in 95 the flange 4 of the stand 1. When it is desired to remove the bag, which has been deposited in the receptacle, the rod 25 is rotated by means of a key, in the possession of an authorized person, said key being engaged with the squared end 26 of the rod. 100

The L-shaped guide member 18 in connection with the plate 19 and extension 20 guide the two sections of the receptacle when closing and brings them into proper position. 105

Having fully described my invention what I claim as new and desire to secure by Letters Patent is:

1. In mail bag receiving means, a supporting post, and a receptacle carried thereby composed of a plurality of sections mounted for movement toward and away from each other and slidably connected at their rear edges whereby, when one of said sections is subjected to pressure adjacent its rear edge, 110 the two said sections are moved toward each other to close the receptacle. 115

2. In mail bag receiving means, a supporting post, and a receptacle carried thereby composed of two rockably mounted sections 120 having their rear edges slidably connected whereby, when one of said sections is subjected to pressure adjacent its rear edge, the two said sections are moved toward each other to close the receptacle. 125

3. In mail bag receiving means, a supporting post, and a receptacle carried thereby composed of two superposed sections mounted for movement toward and away from each other and slidably connected at their 130

rear edges, the upper edge of one side of the lower one of said sections being inclined and said lower section being provided with an opening at the lower end of this inclination.

4. In a mail bag receiving means, a receptacle having a lower section pivotally mounted on a horizontal axis, and a similarly mounted upper section, the axes of the two 10 said sections being in the same vertical plane, and the rear edge of one of said sections being slidably connected to the other section.

5. In mail bag receiving means, a receptacle having a lower section pivotally mounted on a horizontal axis, a similarly mounted upper section, a guide strip secured to the rear portion of the lower section, and a guide member secured to the upper section and 20 engaging about the guide strip so as to slidably connect the two said sections.

6. In mail bag receiving means, a post, two rods secured to said post in superposed spaced relation, and a receptacle carried by 25 said post comprising a lower section pivotally mounted on the lower one of said rods,

and an upper section similarly mounted on the upper one of said rods, the two said sections being slidably connected at their rear edges.

7. In mail bag receiving means, a post, two rods secured to said post in superposed spaced relation, a semi-cylindrical receiving member pivotally mounted on the lower one of said rods, a semi-cylindrical receiving member pivotally mounted on the upper rod of greater interior length than the exterior length of the lower receiving member, a guide strip secured to the lower member in spaced relation thereto and concentric therewith, and a guide member secured to the said upper receiving member and engaging about said guide strip whereby sliding connection is established between the two said receiving members.
